KNOCKDOWN CABINET

Sarah T. Armour, Bono, Ark., assignor of fifty
per cent to Charles H. Armour, Bono, Ark.

Application September 20, 1949, Serial No. 116,833

1 Claim. (Cl. 312—257)

1

This invention relates to shelf structures, and more particularly to a collapsible cabinet adapted to be constructed from wood, metal, plastics or any other suitable material of pleasing appearance.

An object of this invention is to provide a cabinet of a novel and beautiful design which may be easily packed and shipped in an unassembled condition, and which may be readily and easily assembled by a housewife into a strong, rigid, and durable shelved cabinet.

Another object of this invention is to provide a novel and useful kitchen cabinet or the like which may be made in a variety of shapes and sizes, yet which may be easily disassembled and stored away when not in use.

These, together with the various ancillary objects of the invention which will become apparent as the following description proceeds are attained by this collapsible cabinet, a preferred embodiment of which has been illustrated, by way of example only, in the accompanying drawings, wherein:

Figure 1 is a perspective view of the collapsible cabinet comprising the present invention in its assembled state;

Figure 2 is a vertical sectional view as taken along line 2—2 in Figure 1;

Figure 3 is a perspective view of the cabinet collapsed and stocked ready for shipment;

Figure 4 is a perspective view of the back panel used in the collapsible cabinet;

Figure 5 is a perspective view of the collapsible cabinet without the cupboard doors attached thereto;

Figure 6 is a perspective view of one of the cupboard doors; and

Figure 7 is a horizontal sectional view as taken along line 7—7 in Figure 2.

With continued reference to the accompanying drawings wherein like reference numerals designate similar parts throughout the various views, 10 designates the back panel used in the present invention. The back panel is provided with a plurality of horizontally spaced vertically extending elongated apertures 12, 14, 16 and 18. Within each of these apertures is positioned one of a series of vertically disposed parallel side members 20, 22, 24 and 26, each of which are provided with a plurality of vertically spaced horizontal elongated apertures such as indicated at 28 in Figure 2.

Within each of these apertures is inserted the

2

shelves 30, 32 and 34. The rear edge of each of the shelves abuts against the rear panel 10. The front edges of the shelves do not extend as far forward as the vertical side members so as to leave a satisfactory clearance for the insertion of the flush cabinet doors 36 and 38 which are hinged respectively to the side members 20 and 26 as at 40 and 42. The doors are provided with a suitable knob such as 44 and 46 to aid in the opening thereof.

Optionally, the rear panel 10 may be made in sections, each of which will be secured to the others by means of a base of metal or wood which may be secured to the side members 20, 22, 24 or 26 extending through the apertures 12, 14, 16 or 18 respectively in order to completely and positively rigidify the whole collapsible cabinet.

This collapsible cabinet may be made from any of the cabinet woods, or may be optionally made from any suitable metal. When used as a wall cabinet, it is fastened to the wall by metal braces screwed to the rear edge of the side members, such as 20, 22, etc.

Since from the foregoing, the construction and advantages of this collapsible cabinet are readily apparent, further description is believed to be unnecessary.

However, since numerous modifications will readily occur to those skilled in the art after a consideration of the foregoing specifications and accompanying drawings, it is not intended to limit the invention to the precise embodiment of cabinet shown and described, except as required by the scope of the appended claim.

35 Having described the invention, what is claimed as new is:

A shelf structure comprising a rear panel having a plurality of horizontally spaced vertically elongated apertures therethrough, a plurality of 40 horizontally spaced vertically disposed parallel side members each having a plurality of vertically spaced horizontal elongated apertures therethrough, said side members being received in said vertical apertures, a plurality of vertically spaced horizontal shelves extending through said horizontal apertures and abutting said rear panel, and a plurality of front panels, each of said front panels being hingedly secured adjacent one of its 45 vertical edges to one of said side members forming covers for cabinets formed by said side members, said rear panel, and said shelves, said rear panel being made in sections, said sections being 50 hingedly secured together, and rigidifying means

3

secured across said sections, said rigidifying means being attached to said side members.

SARAH T. ARMOUR.
